UNITED STATES PATENT OFFICE.

CHARLES E. McMANUS, OF NEW YORK, N. Y.

SYSTEM FOR MAKING AND HANDLING CORK DISKS.

Application filed December 29, 1921. Serial No. 525,808.

To all whom it may concern:

Be it known that I, CHARLES E. McMANUS, a citizen of the United States, residing at the borough of Manhattan, in the city, 5 county, and State of New York, have invented certain new and useful Improvements in a System for Making and Handling Cork Disks, of which the following is a specification, reference being had therein to the accompanying drawings, which form a part 10 thereof.

My invention relates to a system for making and handling cork disks, and more particularly to an association and combination 15 of mechanisms whereby disks are cut from cork stock, either natural or composition, or from previously formed composition cork rods and delivered to their point of ultimate use, all imperfect disks, broken parts of 20 disks and cork dust, designated generally as waste, being automatically removed from the product of the disk forming or slicing machines before delivery of such disks to their point of ultimate consumption.

Heretofore in the art of making disks for 25 bottle caps, it has been the practice particularly when the disks are cut from composition cord rods, to deliver such cork rods from the baker to the slicing machines, the 30 product of said slicing machines having been accumulated in baskets and the dust, broken particles and imperfect disks, or waste, removed therefrom by mechanical sifters and by hand, the perfect disks after being 35 separated from the imperfect ones and the refuse, being removed by hand and either stored or delivered manually to the bottle cap assembling machines. In some instances, the cork disk feeding mechanisms of 40 such assembling machines were utilized to separate some waste from the disks delivered thereto in bulk. The method of producing and handling such disks in large bulk, has required a large force of men, and 45 the product has not always been satisfactory.

With the above conditions in mind, I have provided a system whereby the product of 50 the disk forming or slicing machines will be automatically removed from adjacent such machines as it is produced, thus permitting the accumulated product of a number of

machines to be simultaneously handled and delivered in volume to one or a plurality of tumbling sieves which will effectively separate imperfect disks and cork particles or dust from the perfect disks, and automatically deliver them to a mechanism which will convey the perfect disks, after the waste has been separated therefrom, to the hoppers of bottle cap assembling machines with 55 which the disks are used.

The mechanisms of a system embodying my invention work entirely automatically, 60 prevent the accumulation of a mass of products of the slicing machines which require separation in order to permit the effective actuation of other separating mechanisms thereon, and avoid any handling of the product after the formed disks have once been 65 delivered by the slicing or forming machines.

The manner of handling the product of the slicing or forming machines before and 70 after it leaves the separators, is such as to 75 secure a partial separation of perfect disks from the waste, so as to facilitate the handling of this product by the separators, and remove any fine dust which may adhere to the disks and be separated therefrom during 80 their motion while in transit from the separators to the bottle cap assembling machines. The system is such that different portions thereof may be utilized or not, as 85 desired, so as to adapt the entire system to the output capacity of the slicing or forming machines and permit variance in the capacity of the entire system through the shutting down of such machines.

In addition to delivering the disks to the 90 bottle cap assembling machines, I provide means whereby, if desired, a portion or all of the disks may be delivered at a point before they reach the assembling machines, 95 since under some conditions these disks are sold as separate articles of commerce instead of being assembled in the metal shell of bottle caps.

The invention consists primarily in a system for making and handling cork disks embodying therein a disk forming mechanism, 100 a pneumatic tube adapted to receive disks from said mechanism, means maintaining a constant circulation of air in said tube,

whereby disks delivered thereto will be conveyed from adjacent said mechanism, a movable screen into which said tube discharges, means adapted to receive disks from said 5 screen, a pneumatic tube into which said means discharges, and means maintaining a constant circulation of air within said last named tube, whereby said disks will be conveyed from said last named means to a point 10 remote therefrom; and in such other novel features of construction and combination of parts as are hereinafter set forth and described, and more particularly pointed out in the claims hereto appended.

15 Referring to the drawings,

Fig. 1 is a condensed plan view showing the arrangement of the different mechanisms entering into the system of my invention; and

20 Fig. 2 is a side view thereof.

Like letters refer to like parts in both of said views.

In the embodiment of my invention shown in the drawings, I have indicated at *a*, *a'* and *a²*, three cork disk slicing machines particularly adapted to separate composition cork rods into disks of the desired thickness. While I have shown but three of these machines, it is apparent that the number 25 thereof may be increased to any desired extent.

The outlets of said machines are indicated at *b*, *b'* and *b²* respectively, said outlets discharging into a pneumatic tube so that the 30 disks as produced in said machines will be discharged directly into openings in said tube irrespective of whether said disks are perfect or imperfect, broken particles of cork or cork dust, being delivered to said 35 tube as an incident to the delivery of the disks thereto.

The pneumatic tube above referred to is indicated at *c* and is shown as being of gradually diminishing diameter or capacity 40 for the purpose of accommodating this tube to a number of disk producing mechanisms arranged in a battery.

Communicating with the tube *c* is the intake of a blower *d* so as to constantly withdraw air from said tube and thus maintain a constant circulation of air toward said blower and maintain a constant suction sufficient to carry the cork disks and waste from adjacent each machine *a*, *a'* and *a²*, such 45 disks and waste being sufficiently light to be readily carried in suspension in the air. When a large battery of disk making machines is used, I also employ at the other end of the tube *c*, a blower *e* which will 50 serve to deliver an air current to, and accelerate the flow of air through, said tube *c*.

By graduating the diameter of said tube *c*, the effective suction adjacent each of the machines *a*, *a'* and *a²* will be substantially 55 equalized, the blower *e* preventing any stag-

nation adjacent the machines of the battery more remote from the blower *d*.

Leading from the offtake of the blower *d* is a pneumatic tube *f* discharging into an inclined agitating screen *g*, or if desired a plurality of such screens, in which the latter case branch pipes *f'* are provided leading from the main pneumatic tube *f* and discharging respectively into a screen *g*. Said screens *g* are preferably in the form of 75 rotating drums having agitators *g'* therein, as shown more particularly in Fig. 2.

In each of the branch pipes *f'* is a cutoff valve *f''* so that one or more of the screens *g* may be used, as desired, the tube *f*, when a plurality of screens *g* are to be served thereby, being of progressively reduced diameter as shown, with the small end thereof closed, thus retarding the movement of the air, and disks and other matter in suspension therein, 80 in a manner to ensure the feeding of such matter to a succession of such screens *g*.

The screens *g* are supported and rotated in any desired manner as by the belts *g''*.

The screens *g* are preferably in barrel 90 form and are covered with a mesh sufficiently large to permit the escape of cork particles, cork dust and imperfect disks therethrough, the movement of said screens constantly agitating the mass of disks therein, to which is constantly added a fresh supply through the branch pipe *f'* so as to secure a separation of the perfect disks from the imperfect ones and waste, and the gradual feeding of the perfect disks toward the 95 low end of the screens from whence they will flow upon a conveyor belt *h*. The disks are conveyed by said belt from adjacent the screen to a pneumatic tube *i*, one end of which communicates with the intake of a 100 blower *j* and the other end of which is closed, said pneumatic tube *i* being of gradually increased diameter so as to ensure an effective application of suction to all parts 105 thereof by the blower *j*.

The upper reach of the belt *h* passes about the pulleys *h'* and *h²* so as to have different portions of said reach upon different horizontal planes and thus cause the turning of all disks as they pass from one 115 portion thereof to the portion upon the lower plane, so that an operator stationed at this point may inspect the disks as they are passing from the screen.

The tubes *c* and *i* are provided with suitable openings to receive the cork disks and waste, the capacity of these openings being insufficient to materially impair the efficiency of the blowers *d* and *j* while ensuring the entrance of the disks to within the 120 tube.

Leading from the discharge end of the blower *j* is a pneumatic tube *k* having discharge openings *k'* in the bottom thereof through which the cork disks may be dis- 125

charged to an elongated hopper *m* having a sequence of outlets *m'* through which said disks may be delivered to chutes *n* adjacent the hopper of a cork feeding mechanism *o* 5 of a bottle cap assembling machine *p*. Said assembling machine is shown merely conventionally, as the details of construction thereof are immaterial to the present invention.

10 The tube *k* is of reduced diameter toward the end thereof most remote from the blower *j*, as shown more particularly in Fig. 1, so as to ensure the desired distribution of the cork disks throughout different portions of 15 the hopper trough *m*.

I employ a plurality of chutes *n*, one adjacent each assembling machine, the trough *m* having a gate *m'* controlling the opening *m'* to each chute *n* so as to permit the cutting off of the supply of disks to any 20 assembling machines.

I also provide each opening in the tube *k* with a gate *k'* so that if desired all or any outlet openings *k'* in the tube *k* may be 25 closed, as when limiting the quantity of disks delivered to the trough *m*, or when it is desired to deliver some or all of said disks to boxes or barrels instead of to the 30 assembling machines.

This delivery of the disks to boxes or barrels is secured through the medium of the vertically extending branch tube *q* leading from the tube *k* intermediate the blower *j* and the trough *m*, the opening between said 35 tube *q* and said tube *k* being controlled by a gate *q'*.

Adjacent the disk cutting or slicing machines *a*, *a'* and *a''* and above same is a platform *r* upon which the workman may 40 stand when feeding cork rods to said machines.

The operation of the herein described mechanism is substantially as follows:—

When producing cork disks, the blowers

45 *d*, *e* and *j* have power applied thereto substantially simultaneously with the application of power to the disk producing machines *a*, *a'* and *a''* and the conveyer mechanism *h* and the screens *g*.

50 As a result of the actuation of the blowers *d* and *e*, air will be withdrawn from adjacent the large end of the pneumatic tube *c* so as to have a tendency to develop a subatmospheric pressure within said tube 55 which is relieved through the openings in said tube into which the outlet chutes *b*, *b'* and *b''* discharge, the air rushing into said tubes through said openings carrying with it disks delivered by the machines *a*, *a'* and *a''* including imperfect disks, particles of cork and cork dust.

The blower *e* will deliver air to the small end of the tube *c* so as to maintain the desired circulation of air, this blower being of 60 lower capacity than the blower *d* and being

designed merely to ensure the development of the desired current of air adjacent the cork disk producing machines more remote from the blower *d*, since if a large battery of such machines is used, the effective suction adjacent the machine most remote from the blower *d* may be insufficient to impart the desired rapid movement to the material delivered by said machines.

The constant current of air through the 75 tube *c* is sufficiently strong to carry the cork disks and incidental waste away from the machines *a*, *a'* and *a''* as rapidly as they are delivered, such material passing through the blower *d* and being delivered into the 80 pneumatic tube *f*, being discharged therefrom through the branch pipes *f'* to the rotary screens *g*, the reduced end of said tube *f* causing the retardation of the air current towards the end of the tube so that a portion 85 thereof with the cork disks and waste will pass through each branch tube *f'* to a barrel screen *g*.

The screens *g* are constantly rotating, and as a result of this rotation, and of the large 90 mesh screen, practically all broken particles, imperfect disks and heavy dust will be sifted from the perfect disks, the mass of perfect disks gradually working longitudinally of the barrel until they are discharged upon the conveyer *h*. The tumbling action of said screens *g* will not only serve to sift the imperfect disks, broken particles and cork dust from the products of the machines *a*, *a'* and *a''* passing therethrough, but will, through 100 the constant agitation of the perfect disks and the rubbing action against the mesh and the baffles of the screen and each other, tend to separate any loose cork dust from the disks so that when they emerge from the 105 screen they will be sufficiently clean to permit them to be packed for shipment, or be used in the assembling machines *p*, as desired.

By looping the conveyer belt *h* about the 110 pulleys *h'* and *h''*, the disks which fall upon this belt flatwise will be automatically turned so that if desired an operator stationed at this point may inspect the disks and remove 115 imperfect ones of a size too large to pass through the meshes of a screen *g*.

The disks are delivered from the belt *h* to the tube *i* connected with the air intake of the blower *j* so as to be conveyed from adjacent each belt *h* as rapidly as they are 120 delivered to said tube *i*, the current of air and the disks carried thereby being delivered through the tube *k* to the trough *m* and then to the hoppers of the cork feeding attachment of the various machines *p*, or if desired, through the branch tube *q* to storage boxes or barrels, or a part may be delivered to said trough and a part to said boxes or barrels.

A system embodying my invention must 130

be so designed as to handle the maximum volume of disks which may be produced in the machines a , a' and a^2 and any desired number of such machines may be used.

5 These machines produce disks with great rapidity, cork rods being fed thereto as required, by a workman upon the platform r .

If it be desired, however, to curtail the capacity of the system this may be done by 10 shutting down any desired number of machines a , a' or a^2 , and reducing the capacity of the screen unit by closing one or more of the gates f^2 , as desired. Since the capacity of the battery a , a' and a^2 will ordinarily be 15 proportioned to the requirement of the battery of assembling machines p , it is apparent that when some of the units of the battery of disk producing machines are inoperative, the gates m^2 and k^2 adjacent 20 some of the assembling machines p should also be closed. In fact by employing the gates f^2 , k^2 and m^2 , the capacity of the system may be controlled throughout.

Under some conditions it is desirable to 25 operate the battery of cork disk producing machines to the full capacity even though conditions do not justify the operation of all assembling machines p of the battery served thereby. Under such conditions 30 some of the gates m^2 and k^2 adjacent the assembling machines p which are not in use, are closed, and the gate q' is open, the surplus product of the disk producing machines then being delivered through the 35 branch tube q where they may be stored in suitable receptacles so that if desired said disks may be used without being assembled in the bottle caps, or may be stored as a reserve for use in the assembling machines 40 when the cork disk producing machines are not operating.

A system embodying my invention has the 45 advantage, in addition to the automatic supply of cork disks to the assembling machines, and the incidental reduction of labor cost in handling the disks, that the disks are kept always clean and uncontaminated by handling or by falling upon the floor adjacent the machines a , a' and a^2 ; are 50 thoroughly cleansed by being passed through the pneumatic tubes and through the screens g , of cork particles and dust, and have but few imperfect disks at the point of ultimate delivery due to the fact 55 that the finer particles of dust are separated from the heavier matter when being delivered to the screens g and are delivered to said screens in rapid succession instead of in bulk so that the imperfect disks and 60 broken particles are more readily and more rapidly separated from the perfect disks while in the screens.

I have discovered by actual practice that 65 the pneumatic transportation of light cork disks, results in less waste and can be much

more rapidly accomplished than the transfer of the disks from point to point of the factory by hand, and that the disks when delivered are in better condition when transported in this manner than when this 70 work is done by hand.

Furthermore, it is possible to widely 75 separate the cork disk producing machines from the bottle cap assembling machines and thus avoid the presence of fumes freed from the cork rods or other material by the action of the cutters thereon, adjacent the assembling machines.

While an effective distribution of disks is 80 secured by the particular arrangement of parts shown in the drawings, it is apparent that this arrangement is immaterial to the invention and may be varied according to a particular desired grouping of mechanisms in a factory, to secure the most effective 85 utilization of floor space.

It is not my intention to limit the invention to the precise details of construction and arrangement of parts shown in the drawings, it being apparent that such may 90 be varied without departing from the spirit and scope of the invention.

Having described the invention, what I 95 claim as new and desire to have protected by Letters Patent, is:—

1. A system for making and handling 100 cork disks embodying therein a disk forming mechanism, a pneumatic tube adapted to receive disks from said mechanism, means maintaining a constant circulation of air in said tube, whereby disks delivered thereto will be conveyed from adjacent said mechanism, a movable screen into which said tube discharges, means adapted to receive disks from said screen, a pneumatic tube into 105 which said means discharges, and means maintaining a constant circulation of air within said last named tube, whereby said disks will be conveyed from said last named means to a point remote therefrom. 110

2. A system for making and handling 115 cork disks embodying therein a disk forming mechanism, a pneumatic tube adapted to receive disks from said mechanism, means maintaining a constant circulation of air in said tube, whereby disks delivered thereto will be conveyed from adjacent said mechanism, a tube leading from said means, a movable screen into which said last named tube discharges, means adapted to receive 120 disks from said screen, a pneumatic tube into which said means discharges, means maintaining a constant circulation of air within said last named tube, whereby said disks will be conveyed from said last named 125 means to a point remote therefrom, a bottle cap assembling machine having a cork disk feeding attachment, a tube leading from said last named means and terminating, and having a discharge opening therein, ad- 130

jacent said assembling machine, and means whereby disks passing through said opening are conveyed to said disk feeding attachment.

5 3. A system for making and handling cork disks embodying therein a disk forming mechanism, a pneumatic tube adapted to receive disks from said mechanism, means maintaining a constant circulation of air in 10 said tube, whereby disks delivered thereto will be conveyed from adjacent said mechanism, a tube leading from said means, a movable screen into which said last named tube discharges, means adapted to receive 15 disks from said screen, a pneumatic tube into which said means discharges, means maintaining a constant circulation of air within said last named tube, whereby said disks will be conveyed from said last named 20 means to a point remote therefrom, a bottle cap assembling machine having a cork disk feeding attachment, a tube leading from said last named means and terminating, and having a discharge opening therein, adjacent 25 said assembling machine, means whereby disks passing through said opening are conveyed to said disk feeding attachment, a branch tube leading from said last named tube intermediate said means maintaining a 30 circulation of air therein and said assembling machine, and a gate controlling said branch tube whereby cork disks may be excluded from, or permitted to pass through, said branch tube.

35 4. A system for making and handling cork disks embodying therein a disk forming mechanism, a pneumatic tube adapted to receive disks from said mechanism, a blower, the inlet of which is connected with said 40 tube, whereby disks delivered thereto will be conveyed from adjacent said mechanism, a tube connected with the outlet of said blower, a movable screen into which said tube discharges, means adapted to receive 45 disks from said screen, a pneumatic tube into which said means discharges, a blower having its inlet connected with said last named pneumatic tube, and a pneumatic tube connected with the outlet of said last 50 named blower, whereby said disks will be conveyed from said blower to a point remote therefrom.

5. A system for making and handling cork disks embodying therein a plurality of disk 55 forming mechanisms, a pneumatic tube adapted to receive disks from said mechanisms respectively, a blower having its inlet connected with said pneumatic tube, said tube being of gradually reduced diameter 60 from adjacent said blower, a second pneumatic tube leading from the outlet of said blower, a movable screen into which said tube discharges, means adapted to receive disks from said screen, a pneumatic tube 65 into which said means discharges, a blower

having its inlet connected with said last named pneumatic tube, and a pneumatic tube connected with the outlet of said last named blower, whereby said disks will be conveyed from said blower to a point remote 70 therefrom.

6. A system for making and handling cork disks embodying therein a plurality of disk forming mechanisms, a pneumatic tube adapted to receive disks from said mechanisms respectively, a blower having its inlet connected with said pneumatic tube, said tube being of gradually reduced diameter 75 from adjacent said blower, a blower having its outlet connected with the small end of 80 said tube, a second pneumatic tube leading from the outlet of said first named blower, a movable screen into which said tube discharges, means adapted to receive disks from said screen, a pneumatic tube into which 85 said means discharges, a blower having its inlet connected with said last named pneumatic tube, and a pneumatic tube connected with the outlet of said last named blower, whereby said disks will be conveyed from 90 said blower to a point remote therefrom.

7. A system for making and handling cork disks embodying therein a plurality of disk forming mechanisms, a pneumatic tube adapted to receive disks from said mechanisms respectively, a blower having its inlet connected with said pneumatic tube, said tube being of gradually reduced diameter from adjacent said blower, a second pneumatic tube leading from the outlet of said 100 blower, a plurality of movable screens, branch tubes leading from said second pneumatic tube and discharging into said screens respectively, means adapted to receive disks from said screens respectively, a pneumatic tube into which said last named means respectively discharge, a blower having its inlet connected with said last named pneumatic tube, and a pneumatic tube connected with the outlet of said last named blower, 105 whereby said disks will be conveyed from said blower to a point remote therefrom.

8. A system for making and handling cork disks embodying therein a plurality of disk forming mechanisms, a pneumatic tube adapted to receive disks from said mechanisms respectively, a blower having its inlet connected with said pneumatic tube, said tube being of gradually reduced diameter from adjacent said blower, a second 115 pneumatic tube leading from the outlet of said blower, a plurality of movable screens, branch tubes leading from said second pneumatic tube and discharging into said screens respectively, means adapted to receive disks 120 from said screens respectively, a pneumatic tube into which said last named means respectively discharge, said last named tube being of gradually increasing diameter from adjacent said last named means, a blower 125

65 130

having its inlet connected with the large end of said last named tube, a pneumatic tube connected with the outlet of said last named blower, whereby said disks will be 5 conveyed from said blower to a point remote therefrom.

9. A system for making and handling cork disks embodying therein a plurality of disk forming mechanisms, a pneumatic tube 10 adapted to receive disks from said mechanisms respectively, a blower having its inlet connected with said pneumatic tube, said tube being of gradually reduced diameter from adjacent said blower, a second pneumatic tube 15 leading from the outlet of said blower, a plurality of movable screens, branch tubes leading from said second pneumatic tube and discharging into said screens respectively, means adapted to receive disks 20 from said screens respectively, a pneumatic tube into which said last named means respectively discharge, said last named tube being of gradually increasing diameter from adjacent last named means, a blower having 25 its inlet connected with the large end of said last named tube, a plurality of bottle cap assembling machines each having a cork disk feeding attachment, a pneumatic tube leading from the outlet of said last named 30 blower and extending adjacent each of said assembling machines, and having openings therethrough, and means adapted to receive cork disks from said last named tube and deliver them to said cork feeding attach- 35 ments respectively.

10. A system for making and handling cork disks embodying therein a plurality of disk forming mechanisms, a pneumatic tube adapted to receive disks from said mechanisms respectively, a blower having its inlet connected with said pneumatic tube, said tube being of gradually reduced diameter from adjacent said blower, a second pneumatic tube leading from the outlet of said 45 blower, a plurality of movable screens, branch tubes leading from said second pneumatic tube and discharging into said screens respectively, means adapted to receive disks from said screens respectively, a pneumatic 50 tube into which said last named means respectively discharge, said last named tube being of gradually increasing diameter from adjacent said last named means, a blower having its inlet connected with the large end 55 of said last named tube, a plurality of bottle cap assembling machines each having a cork disk feeding attachment, a pneumatic tube leading from the outlet of said last named blower and extending adjacent each of said 60 assembling machines, and having openings therethrough, means adapted to receive cork disks from said last named tube and deliver them to said cork feeding attachments respectively, and a gate adapted to close the 65 opening in said last named tube adjacent

each assembling machine, said tube adjacent said assembling machines being of gradually decreasing diameter from adjacent said blower.

11. A system for making and handling 70 cork disks embodying therein a plurality of disk forming mechanisms, a pneumatic tube adapted to receive disks from said mechanisms respectively, a blower having its inlet connected with said pneumatic tube, 75 said tube being of gradually reduced diameter from adjacent said blower, a second pneumatic tube leading from the outlet of said blower, a plurality of movable screens, branch tubes leading from said second pneumatic tube and discharging into said screens respectively, means adapted to receive disks 80 from said screens respectively, a pneumatic tube into which said last named means respectively discharge, said last named tube 85 being of gradually increasing diameter from adjacent said last named means, a blower having its inlet connected with the large end of said last named tube, a plurality of bottle cap assembling machines each having 90 a cork disk feeding attachment, a pneumatic tube leading from the outlet of said last named blower and extending adjacent each of said assembling machines, and having openings therethrough, means adapted to receive cork disks from said last named tube and deliver them to said cork feeding attachments respectively, a branch tube leading 95 from said last named tube between said assembling machines and said blower, and a gate whereby said branch tube may be opened or closed, as desired.

12. A system for making and handling 100 cork disks embodying therein a plurality of disk forming mechanisms, a pneumatic tube adapted to receive disks from said mechanisms respectively, a blower having its inlet connected with said pneumatic tube, said tube being of gradually reduced diameter from adjacent said blower, a second pneumatic tube leading from the outlet of said blower, a plurality of movable screens, branch tubes leading from said second pneumatic tube and discharging into said screens respectively, a gate in each of said 110 branch tubes whereby the products of said disk forming mechanisms may be delivered to any or all of said screens, means adapted to receive disks from said screens respectively, a pneumatic tube into which said last named means respectively discharge, said last named tube being of gradually increasing diameter from adjacent said last named means, a blower having its inlet connected with the large end of said last named tube, a plurality of bottle cap assembling machines each having a cork disk feeding attachment, a pneumatic tube leading from the outlet of said last named blower and extending adjacent each of said assembling 125 machines 130

machines, and having openings therethrough, means adapted to receive cork disks from said last named tube and deliver them to said cork feeding attachments respectively, and a gate adapted to close the opening in said last named tube adjacent each assembling machine, said tube adjacent said assembling machines being of gradually decreasing diameter from adjacent said blower. 5

13. A system for making and handling cork disks embodying therein a plurality of disk forming mechanisms, a pneumatic tube adapted to receive disks from said mechanisms respectively, a blower having its inlet 10 connected with said pneumatic tube, said tube being of gradually reduced diameter from adjacent said blower, a second pneumatic tube leading from the outlet of said blower, a plurality of movable screens, 15 branch tubes leading from said second pneumatic tube and discharging into said screens respectively, a gate in each of said branch tubes whereby the products of 20 said disk forming mechanisms may be delivered to any or all of said screens, means adapted to receive disks from said screens respectively, a pneumatic tube into which said last named means respectively discharge, said last named tube being of gradually 25 increasing diameter from adjacent said last named means, a blower having its inlet connected with the large end of said last named tube, a plurality of bottle cap assembling machines each having a cork disk 30 feeding attachment, a pneumatic tube leading from the outlet of said last named blower and extending adjacent each of said assembling machines, and having openings therethrough, means adapted to receive cork disks 35 from said last named tube and deliver them to said cork feeding attachments respectively, a gate adapted to close the opening in said last named tube adjacent each assembling machine, said tube adjacent said assembling machines being of gradually decreasing diameter from adjacent said blower, a branch tube leading from said last named tube between said assembling machines and said blower, and a gate whereby 40 said branch tube may be opened or closed, as desired. 45

14. A system for making and handling cork disks embodying therein a plurality of disk forming mechanisms, a pneumatic tube adapted to receive disks from said mechanisms respectively, a blower having its inlet connected with said pneumatic tube, said tube being of gradually reduced diameter from adjacent said blower, a second blower 50 having its outlet communicating with the small end of said tube, a second pneumatic tube leading from the outlet of said blower, a plurality of movable screens, branch tubes 55 leading from said second pneumatic tube and discharging into said screens respectively, a pneumatic tube into which said last named means respectively discharge, a blower having its inlet connected with said last named pneumatic tube, and a pneumatic tube connected with the outlet of said last named blower, whereby said disks will be conveyed from said blower to a point remote therefrom. 60
